(57) **CLAIM**

The ornamental design for a tool attachment panel as shown and described.

DESCRIPTION

FIG. 1 is a perspective view of an embodiment of my new design;

FIG. 2 is a back perspective view thereof;

FIG. 3 is a front view thereof;

FIG. 4 is a back view thereof;

FIG. 5 is a right side view thereof;

FIG. 6 is a left side view thereof;

FIG. 7 is a top view thereof;

FIG. 8 is a bottom view thereof;

FIG. 9 is a perspective view of another embodiment of my new design;

FIG. 10 is a back perspective view thereof;

FIG. 11 is a front view thereof;

FIG. 12 is a back view thereof;

FIG. 13 is a right side view thereof;

FIG. 14 is a left side view thereof;

FIG. 15 is a top view thereof; and,

FIG. 16 is a bottom view thereof.

Any unshaded surfaces shown in broken lines or between solid and broken lines form no part of the claimed design. The broken lines in the drawings depict portions of the tool attachment panel that form no part of the claimed design.

1 Claim, 12 Drawing Sheets
